Attorney

UNITED STATES PATENT OFFICE.

HARVEY L. WATKINS, OF PHILADELPHIA, PENNSYLVANIA.

GAME.

1,275,805.

Specification of Letters Patent. Patented Aug. 13, 1918.

Application filed September 18, 1917. Serial No. 191,957.

To all whom it may concern:

Be it known that I, HARVEY L. WATKINS, a citizen of the United States, and resident of Philadelphia, in the county of Philadelphia and State of Pennsylvania, have invented certain new and useful Improvements in Games, of which the following is a specification.

The present invention relates to the class 10 of games and toys and has particular reference to new and useful improvements in a game of chance.

The primary object of my invention is to provide a device of the character mentioned 15 that is simple in construction, efficient in operation and that can be manufactured and placed on the market at a minimum cost.

A still further object of my invention is to provide a game that will interest and 20 amuse children and at the same time provide means for small children to readily learn the alphabet and numerals.

Other improvements and novel details in the construction and arrangement of the 25 various parts of the game board will be brought out more in detail in the description to follow, which, for a clear understanding of the invention, should be considered in connection with the accompanying drawing, forming a part hereof, and wherein is disclosed, for the purpose of illustration, 30 convenient and satisfactory embodiments of the invention. It is to be noted, in this connection, that minor changes in the construction and arrangement of the various parts 35 may be made without departing from the spirit of the invention or the principle of operation thereof.

In the drawing:

40 Figure 1 is a top plan view of my game apparatus, and

Fig. 2 is a transverse section thereof.

Referring now more particularly to the drawing, wherein like reference characters 45 designate corresponding parts throughout the several views thereof, my invention comprises a pair of superposed rectangular members preferably of sheet metal having numerals arranged along the outer edges of 50 the lower member in series of twenty-five

while the upper member is provided with letters of the alphabet along the outer edges thereof.

The lower member designated 1 and hereinafter known as the numeral board comprises a sheet metal member of a rectangular configuration having numerals arranged along the outer edges thereof in series of twenty-five for a purpose which will hereinafter appear. The upper member which is arranged in spaced relation relative to the lower member is designated 2 and will hereinafter be known as the alphabetic board and is provided with letters of the alphabet along the outer edges thereof. 55

The alphabetic board and the numeral board are connected by means of a rivet member 3 and washers 4 which are mounted on the outer surfaces of the board. Interposed between the board members is a comparatively smaller washer 5 for an obvious purpose. It is of course obvious that the rivet member extends through an opening 6 that is arranged concentrically of the board members. The rules of the game are as 70 follows: Each of the participants of the game selects the letter preferably the first letter of his name and then proceeds to rotate the alphabetic board 2, and after the same has come to a stop seeks the letter originally retained and selects the numeral closest the same along the outer edges of the lower board. This procedure is gone through with, two or three times, *i. e.*, the 75 rotating of the upper board and the selecting of the numerals nearest thereto by each member. After each member has gone through this procedure the participant having the lowest total sum is considered the 80 winner of the game. 85

It is of course to be understood that the above description and accompanying drawing comprehend only the general embodiment of my invention and that various minor changes in detail of construction, proportion and arrangement of parts may be made within the scope of the appended claim and without sacrificing any of the advantages of my invention. 95

Having thus fully described my invention, 100

what I claim as new, and desire to secure by Letters Patent, is:

In a device of the character described the combination of a pair of rectangular members arranged in superposed spaced relation, the lower member having numerals arranged on the outer edges thereof, the upper mem-

ber having letters of the alphabet arranged along the outer edges thereof, and the upper member being adapted to rotate on the lower 10 member for a purpose specified.

In testimony whereof, I affix my signature hereto.

HARVEY L. WATKINS.
